(57) **CLAIM**

The ornamental design for combined barbecue shelves and console, as shown.

DESCRIPTION

FIG. 1 is an isometric view of combined barbecue shelves and console showing the new design;

FIG. 2 is a front view of the combined barbecue shelves and console of FIG. 1;

FIG. 3 is a side view of the combined barbecue shelves and console of FIG. 1; and,

FIG. 4 is a top view of the combined barbecue shelves and console of FIG. 1.

The design is shown and described in solid lines in the drawings. The broken lines in the drawings form no part of the claimed design.
